UNITED STATES PATENT OFFICE

MARTIN L. NELSON, OF PARK RIDGE, ILLINOIS, ASSIGNOR, BY MESNE ASSIGNMENTS, TO AUTOMATIC ELECTRIC INC., OF CHICAGO, ILLINOIS, A CORPORATION OF DELAWARE

MULTIOFFICE TELEPHONE SYSTEM

Application filed January 9, 1928, Serial No. 80,167. Renewed June 2, 1928.

The present invention relates to multi-office telephone systems in general, but is concerned more particularly with multi-office telephone systems in which directors are employed to register the office designations of the calls and direct the calls to the designated offices, and to register and retransmit the subscriber-designating digits of the number in order to complete the connection to the de-

10 sired station.

The present invention is directed to a number of points in the operation of a comprehensive director system among which appear the following outstanding points:

15 One object of the invention is to bring about a reduction in the number of terminals required on the office-register side of the intermediate distributing frame by connecting certain contact sets in the bank of the 20 office register to the same set of terminals in case the wipers of the office register are brought into engagement with the several sets of bank contacts in response to the dialing of equivalent designations as will hereinafter appear.

Another object of the invention is to arrange the director so that it normally responds to and retransmits four subscriber digits, but will respond to and retransmit 30 five subscriber digits in case the first two subscriber digits received are such as to indicate that the number being called a five digit number.

Another object of the invention is to provide a director which after registering four 35 digits in a number that is not a regular five digit number will wait a sufficiently long period of time to enable the calling subscriber to dial a party-designating digit before switching through so that those lines which are reached by the calling of four subscriber digits may be reached by party line connectors provided with a party selecting switch operated by the receipt of a party- 40 designating digit after the connector has 45 been set upon the called line.

Another object of the invention has to do with arrangements for freeing the director in case a calling subscriber delays dialing 50 for longer than a predetermined time, and

consists in the provision of a desirable arrangement whereby a reasonably long time is allowed after the removal of the receiver and before the dialling of the first digit to permit the calling subscriber to recall the 55 number, together with the arrangement whereby, after the first digit has been dialled, a considerably shorter time is allowed between the dialling of successive digits.

A further object of the invention is the 60 production of a new and improved cam-type impulse sender, and more specifically of the type which completes its cycle of operations upon the transmission of each digit and starts over again for the following digit, as distinct 65 from the type in which the transmission of a complete number constitutes a single cycle of operations. It is more specifically an object to provide a cam sender of the above type having improved pick-up and stop 70 circuits for starting and stopping the impulses in an outgoing control circuit separate from the pick-up and stop circuits themselves.

A further object is the production of a 75 new and improved timing system whereby the timing devices individual to separate directors may be all operated from a common source of power to which they are connected and from which they are disconnected each under the control of the associated 80 director.

In addition to the foregoing outstanding objects of the invention, there are a number of more or less minor objects and special features.

One object of the latter class is the provision of suitable circuit arrangements whereby the timing device which is started into operation upon the registration of the fourth subscriber digits is prevented from 90 switching the connection through and freeing the director at the end of the interval for which it is adjusted in case all the registered digits have not been transmitted at the end 95 of such interval.

A further object of the latter class has to do with the provision of arrangements for preventing the director from switching through at the end of the transmission of the fourth subscriber digit in cases when the 100

predetermined time interval has already elapsed when the transmission of the fourth subscriber digit is effected, provided the fifth digit register has been operated.

There are other objects and features of the invention which for the most part have to do with the circuit details, which objects and features will become apparent upon a further perusal of the specification.

Referring now to the accompanying drawings comprising Figs. 1-8, Figs. 1-6 show by means of the usual circuit diagrams certain apparatus in a system embodying the principles of the invention; Fig. 7, is a top view of a calling device of the type assumed to be used at the substations of the system under consideration; and Fig. 8, is a table showing that certain sets of contacts in the bank of the office register of the director connect to pin terminals on the intermediate distributing frame in common with one or more other sets of contacts.

Referring now particularly to Fig. 7, it will be noted that all the letters of the alphabet, with the exception of the letters Q and Z, appear through the finger holes 2-9 of the finder hold dial of the calling device. These letters are placed on the calling device so as to enable the calling subscriber to call office designations by means of combinations of letters rather than by means of combinations of numerals. For example, in a system in which two office-designating digits are used, the calling subscriber dials those digits by selecting the holes through which appear the corresponding letters. For example, the telephone number Main 4926 is listed in the telephone directory as MAin 4926. It will be noted that the dialling of MA, with the calling device shown, is the same as dialling 62, but the telephone numbers are much more easily remembered in case they are listed in this manner.

Similarly, in case three office-designating digits are used, the first three letters of the office name are used and the number Main 4926 is listed in the directory as MAIn 4926. It will be noted that the numerical equipment of the designation MAI is 624.

It will be noted that there are no letters appearing through the first and tenth finger holes. The reason for this will now be explained. It often occurs that a subscriber, on removing his receiver, inadvertently jars the telephone, or strikes the receiver against the hook after it has been raised and before it has been sufficiently removed, with the result that a single interruption is produced in the line circuit after it has been closed. This momentary interruption has the same effect upon the exchange apparatus as the calling of the digit 1. Accordingly it has been arranged so that no office designation begins with the digit 1 with the result that the registration of the digit 1 at the exchange can

be always wiped out in case the digit 1 is the first one received.

Regarding the absence of letters from the tenth position of the calling device, it may be pointed out that the single digit 0 is ordinarily used to trunk the call to an operator. In certain instances the operator reached when the digit 0 is dialled is the toll-recording operator. In other instances the operator reached when the digit 0 is dialled is not the toll-recording operator but is a special operator known as the "zero" operator who is assigned the duty of rendering assistance in completing the connection in case the subscriber is having difficulty in obtaining a certain number and therefore dials the digit 0 to solicit the aid of the zero operator.

Referring now particularly to the circuit drawings including Figs. 1-6, Fig. 1, shows the selector S accessible to the line switches through the conductors 5, 6, and 7. This drawing shows the trunk circuit TC which is inserted in the trunk between the banks of the line switches and the selector S, and also the secondary switch SS, which is individual to the trunk. The trunk circuit TC is provided for the purpose of enabling a director to be associated with the connection to handle the call. The secondary switch SS has access to a number of director selectors one of which is shown in Fig. 2, and it is provided in order to reduce the number of director selectors, as the director selector is required only while the connection is being set up.

The director selector DS, shown in Fig. 2, is, from a mechanical standpoint, similar to the selector S, Fig. 1, in that it is a vertical and rotary switch having sets of bank contacts arranged in horizontal rows or levels.

The director selector is used to select the group of directors corresponding to the first letter dialled. That is, the directors are arranged in eight groups, one for each of the holes of the calling device through which appear the letters of the alphabet.

On one level, the director selector DS has access to the director shown in Figs. 3-6 and to other similar directors.

Since the director selector Fig. 2 responds to the first digit dialled, this switch is arranged to absorb the digit 1. When it responds to the digit 1 the director selector DS restores its shaft and wipers to normal preparatory to responding to a subsequently dialled digit, as the digit 1 does not form part of any number when it is received as the first digit. Another point in connection with the director selector DS is that, whereas the levels 2-9 lead to eight groups of directors that handle regular calls, each of the trunk lines from the tenth level of the director selector leads to a special director which, upon being seized transmits the digits necessary to trunk the call to the zero operator. These special directors are not shown herein but they may

be similar to the 0-level directors disclosed in the British Patent 194,580.

Since the director selector DS, Fig. 2 is seized immediately upon the removal of the receiver, this selector is provided with a timing device, including the cam 101 and the clutch magnet 102, which operates the special switch-through springs 103. This timing device begins to operate when the director selector is seized, and in case no dialling occurs during thirty seconds the springs 103 close with the result that the connection is switched through to the selector S, Fig. 1, in a manner to be pointed out more in detail hereinafter.

In case a digit is received before the 30-second time interval is up, the director selector operates in the usual manner to extend a connection to an idle director, for example, the one shown in Figs. 3-6. When this occurs the timing arrangement shown in the left-hand end of Fig. 5, starts to operate with the result that if no digit is received within the next ten seconds the call is switched through but the connection is first extended to a monitoring operator in a manner to be hereinafter pointed out. The arrangements are such that the timing device is released after the dialling of each digit so that the calling subscriber is allowed ten seconds in any case after the preceding digit has been dialled, except following the fourth digit of a number indicating a line reached by four digits. In this case the 5-second cam of the timing device shown on the left hand end of Fig. 5 comes into play with the result that if the calling subscriber does not dial a party selecting digit within five seconds the call is switched through under the assumption that the line called is not a party line. It will be noted that the 10-second cam is arranged to release any partially set up connection and dial up the number of the monitoring operator, whereas the 5-second cam is merely a switch-through cam as will be hereinafter pointed out.

It may be conveniently pointed out at this time that the portion of the director shown in Fig. 3 comprises the sequence switches SE and SE', together with certain relays. The sequence switch SE is provided for the purpose of distributing the series of incoming impulses to the operating magnets of the registers in turn. The sequence switch SS' is provided for the purpose of rendering the various registers of the director operative one after the other to control the operation of the sender.

The portion of the director shown in Fig. 4 comprises the cam sender shown on the right hand end of the sheet, together with certain relays.

The portion of the director shown in Fig. 5 comprises the office register OR and the intermediate distributing frame I.D.F. The office register mechanically is similar to the

director selector DS, Fig. 2, and to the selector S, Fig. 1, in that its bank contacts are arranged in ten horizontal rows or levels with ten sets of bank contacts in each level. This drawing shows also the timing device TD which is used to time the operations in a manner explained generally hereinbefore and to be explained more in detail hereinafter.

The portion of the director shown in Fig. 6 includes the digit registers DR-1-DR-5 together with the relays 506 and 507. The mechanical construction of each of the digit registers shown in this drawing is substantially the same as the mechanical construction of the sequence switch SE, Fig. 3. That is, each switch has an operating magnet that moves the wiper assembly in a single plane, and a release magnet that subsequently restores the wiper assembly to normal.

Regarding the mechanical construction of the sequence switch SE', Fig. 3, it may be pointed out that this mechanical construction is indicated diagrammatically in the drawings from which it may be seen that the wipers are advanced upon the back stroke of the stepping magnet 217 and that no release magnet is provided, the stepping magnet being merely reoperated step-by-step to advance the wipers to their normal position.

The mechanical construction of the secondary switch SS, Fig. 1, is similar to that of the sequence switch SE, Fig. 3. It may be pointed out, however, that no provisions are made for advancing the secondary switch SS to a normal position at the end of each call. Instead, the wipers of the secondary switch SS are advanced one step at the end of each call in a manner to be pointed out hereinafter so as to give a distribution of traffic such that the next call coming in over the trunk line associated with the secondary switch SS will not take the same director selector.

Regarding the mechanical construction of the timing device TD, Fig. 5, it may be pointed out that this timing device includes an armature 404 associated with the clutch magnet 405, the ratchet segment 403, and the cams 401 and 402. There is a shaft 406 constantly rotating and common to a plurality of timing devices. This rotating shaft is provided with wings 407 and 408. In its normal position the segment 403 is out of reach of the wings 407 and 408 of the common shaft, and the teeth of the segment 403 are out of reach of the retaining spring 409. When the clutch magnet 405 energizes, however, the armature 404 moves to the right bringing the segment 403 into such a position that when it is rotated in a counter clockwise direction the retaining spring 409 maintains it in its position. In this position of the segment 403, the said segment is advanced one step in a counter clockwise position each time one of the wings of the shaft 406 ro-

tates by the teeth of the segment. In the operated position of the armature 404, the cams 401 and 402 are brought to the right so that they are in position to operate the associated springs when the segment 403 has been advanced a sufficient number of steps. When the clutch magnet 405 deenergizes, the armature 404 moves to the position shown in the drawings whereupon the teeth of the segment 403 are disengaged from the retaining spring 409 with the result that the segment 403 and the cams 401 and 402 assume the position shown in the drawing.

The timing devices TD', Fig. 2, and TD², Fig. 3, are of similar construction, but the armatures and locking segments have not been shown so as not to unduly complicate the drawings. It will be noted that the cams of the timing devices TD' and TD² are each labeled "30-second cam", whereas the cams of the timing device TD, Fig. 5, are labeled "ten-second cam and five-second cam," respectively. Accordingly, the timing devices TD' and TD² are operated at a slower rate than the timing device TD. This may be accomplished by providing a common operating shaft such as 406 except that it runs at a correspondingly slower rate.

Four-digit party-line call

The disclosure in the drawings having been described generally, a detailed description of the operation will now be given. For this purpose it will be assumed that a certain calling subscriber desires to converse with the subscriber whose number is listed in the directory as WICHita 6826 J. This number it may be pointed out is a four-digit party-line number. That is, in addition to the exchange designation, the number contains four digits to designate the line, and the party designating character J which designates the desired station on the called line.

It will be assumed that when the above mentioned calling subscriber removes his receiver, the line switch individual to the calling line seizes the trunk circuit TC, Fig. 1, at the terminals 2-4. When this occurs line relay 8 of the trunk circuit TC energizes over conductors 5 and 7 and over the calling line. Upon so doing, line relay 8 closes at armature 14 a circuit from ground through release relay 9, the working contact and armature 14, and through the switch-through relay 10 to battery. Relay 9 energizes over this circuit but relay 10 does not operate owing to the fact that it is shiftly adjusted. Upon operating, release relay 9 places ground on release trunk conductor 6 at armature 15 so as to guard the trunk against seizure and to maintain the calling line switch operated; connects test wiper 32 of the secondary switch SS to the junction of the winding of switching relay 11 and stepping magnet 30 at armature 18; and at armature 17 closes a

circuit through switching relay 11 and stepping magnet 30 in series.

From this point the operation depends upon whether the trunk upon which the wipers of the secondary switch SS are standing is idle or busy. If this trunk is idle, the connection of test wiper 32 to the junction of the winding of switching relay 11 and the stepping magnet is of no consequence and switching relay 11 energizes right away, seizing the trunk.

If, however, the trunk is busy, there is a ground potential encountered on the busy test contact by test wiper 32 with the result that switching relay 11 is short circuited, and does not energize. This same ground potential provides an operating circuit for stepping magnet 30. Stepping magnet 30, being self interrupting, operates in a buzzer like manner and advances the wipers 31-34 step-by-step in search of an idle trunk. Assuming that the trunk comprising conductors 35-38 is the first one found to be idle, the wipers of the secondary switch SS stop when this trunk is reached on account of the fact that there is no ground potential encountered on the test contact by test wiper 32. Stepping magnet 30 does not energize at this time owing to the high resistance of switching relay 11, but switching relay 11 energizes; connects up the outgoing impulse wipers 31 and 34 at armatures 25 and 29; disconnects at armature 26 release trunk conductor 6' from release trunk conductor 6 so as to enable any partially set up connection, including the selector S, to be released without releasing the calling line switch; prepares the impulse circuit at armature 28; and at armature 27 disconnects test wiper 32 from the junction of its own winding and that of stepping magnet 30 and connects it to ground instead, thereby making the seized trunk busy.

As a result of the seized trunk being made busy by the application of ground potential to the release trunk conductor 36, release relay 104 of the director selector DS, Fig. 2, to which the seized trunk extends, energizes over conductor 36. At armature 116, relay 104 closes a circuit for the clutch magnet 102 of the timing device TD' with a result to be described more in detail hereinafter; it opens a point in the circuit of release magnet 108 and places ground on conductor 117 at armature 121; and at armature 122 connects up the lead 137 from the dial tone transformer. When this occurs, current from the secondary winding of the dial tone transformer flows through off-normal spring 110 and its lower contact, resistance 115, lower portion of the three plate condenser 113, normally closed contacts controlled by the eleventh-rotary-step spring 110, conductor 87, wiper 33, armature 28 and its working contact, the small tone condenser 13, and the rest- 130

ing contact and armature 24 to the lower talk-
ing conductor 7. From this point, the tone
current flows back to the calling line and is
provided with a return path to ground over
the upper line conductor, and over conductor
5 from which point it flows through arma-
ture 19 and its resting contact and the up-
per winding of the line relay 8 to ground
through the exchange battery.

10 Upon hearing the tone produced by the
flow of the dial tone current, the calling sub-
scriber knows that the exchange apparatus
is in readiness for him to begin to call the
number.

15 When the calling device is manipulated in
accordance with the first character W in
the desired number, nine interruptions are
produced in the circuit of line relay 8 of the
trunk circuit TC, Fig. 1, as the letter W ap-
pears through the ninth hole in the calling
device, Fig. 7. Each time line relay 8 falls
back, it places ground at the normally closed
contacts controlled by armature 14 on the
impulse conductor 39, at the same time dis-
connecting the switch-through relay 10 from
such conductor at armature 14. This op-
eration short circuits the release relay 9 and
provides an operating circuit for the vertical
magnet of the director selector DS, Fig. 2.

20 The release relay 9 does not fall back dur-
ing the deenergizations of line relay 8, even
though it is short circuited each time line relay 8 falls back as a short circuited relay
is slow to release. The circuit of the ver-
tical magnet of the director selector DS,
Fig. 2, is as follows: from ground by way
of the impulse conductor 39, working con-
tact and armature 28, wiper 33, conductor
37, normally closed contacts controlled by

25 the eleventh-rotary-step spring 110, normal-
ly closed contacts controlled by armature
129, series relay 105, and vertical magnet 118
to battery. Vertical magnet 118 and the
series relay 105 are unable to operate in
series with the relatively high resistance re-
lease relay 10 of the trunk circuit TC, but
the series relay 105 and vertical magnet 118
both energize when the said release relay is
short circuited by the line relay. Each time
30 the line relay energizes following a deen-
ergization produced by the calling device, it
reestablishes the circuit of the release relay
through the switch-through relay 10 and over
the operating conductor. The vertical
35 magnet 118 quickly deenergizes in response
to this operation, but the slow acting relay
105 remains operated throughout the series
of impulses. At armature 124, relay 105
opens a point in the special release circuit.

30 At armature 123, relay 105 prepares a cir-
cuit for stepping relay 106 and opens a point
in the circuit of rotary magnet 114.

When the switch shaft has raised the
wipers as far as the second level, the special
35 release-control springs shift. At contacts

111 a point in the special release circuit is
opened, and at contacts 112 the circuit of step-
ping relay 106 is closed, relay 105 being ener-
gized. Relay 106 operates over this circuit
and closes a locking circuit for itself at arma-
ture 125 which includes the interrupter con-
tacts 132 of the rotary magnet 114. At arma-
ture 126 relay 106 prepares a circuit for the
rotary magnet.

When the series of impulses is terminated,
75 the slow acting series relay 105 falls back and
closes at armature 124 a point in the special
release circuit, but this circuit is not com-
pleted owing to the fact that contacts 111 are
open, as the shaft has been raised above the
80 first level of bank contacts. At armature
123, relay 105 opens the initial circuit of step-
ping relay 106 and completes the circuit of
the rotary magnet through the working con-
tact and armature 126. Rotary magnet 114
85 now energizes and advances the wipers
133-136 into engagement with the first set of
bank contacts in the ninth level. Near the
end of its stroke, rotary magnet 114 opens the
circuit of relay 106 at interrupter contacts 132,
90 whereupon relay 106 falls back and opens a
further point in its circuit of armature 125,
at the same time opening the circuit of rotary
magnet 114 at armature 126. Rotary magnet
114 now falls back and closes the interrupter
95 contacts 132 again.

From this point the operation depends
upon whether the trunk line terminating in
the first set of bank contacts is busy or idle.
If this trunk line is idle, switching relay 107
100 energizes in series with stepping relay 106,
but stepping relay 106 does not operate on
account of the relatively high resistance of
relay 107.

Assuming that the trunk line is busy,
105 switching relay 107 is short circuited and
stepping relay 106 is operated by the ground
potential encountered on the busy test con-
tact by test wiper 135. The operation of
stepping relay 106 results in the closure at
110 armature 126 of an energizing circuit for
rotary magnet 114. The wipers are accord-
ingly advanced another step whereupon relay
106 again falls back when it is opened at con-
tacts 132.

115 This alternate operation of relay 106 and
magnet 114 continues until an idle trunk line
is reached, which trunk line, it will be as-
sumed, is the one comprising conductors
35-38'. When this idle trunk is reached,
switching relay 107, being no longer short cir-
cuated, energizes in series with relay 106
which, as above pointed out does not energize
on account of the relatively high resistance of
switching relay 107. Upon operating, switch-
ing relay 107 opens the circuit of clutch mag-
net 102 at armature 128; it disconnects test
wiper 135 from the test circuit at armature 130
and connects it to ground, thereby making the
seized trunk busy; extends the incoming im-
130

pulse conductor 37 through to wiper 134 at armature 129, at the same time cutting off the branch leading to the vertical magnet 118; and at armatures 127 and 131 connects the outgoing impulse conductors 35 and 38 to the wipers 133 and 136. This latter operation results in the energization of the line 51 of the selector S, Fig. 1, over conductors 5' and 7', through contacts of relays 10 and 11, wipers 31 and 34, conductors 35 and 38, armatures 127 and 131 and their working contacts, wipers 133 and 136, conductors 35' and 38', and the outgoing impulse control circuit of the director, which includes the resting contact and armature 222, Fig. 3, conductor 242, armature 308 and its resting contact, Fig. 4, and armature 317 and its resting contact of relay 306, in multiple with the sending contacts controlled by cam 341. Line relay 51 of the selector S, upon energizing, closes at armature 56 a circuit for release relay 52. Relay 52 energizes and places ground on the release trunk conductor 6' at armature 57, and at armature 58 opens a point in the circuit of release magnet 66 and prepares a circuit for vertical magnet 68.

In the seized director, the grounding of release trunk conductor 37' by switching relay 107 of the director selector DS, Fig. 2, results in the energization of release relay 304, Fig. 4, through armature 315 and its resting contact. Upon operating, relay 304 opens certain normal restoring circuits at armature 312 and 314; it places ground on conductor 247 at armature 313, which results in a ground potential being extended over conductor 247 and through armature 226 and its resting contact to wiper 212 of the sequence switch SE; and at armature 322 it closes a circuit over conductor 252 and through the jumper 418 for the clutch magnet 405 of the timing device TD, ground potential being applied to the working contact of armature 322 from armature 203 of relay 201 and its resting contact, resting contact and armature 230, and conductor 249.

When the calling subscriber dials the second character I of the number, four impulses of current are transmitted over the impulse conductor 37 to the director selector DS and through the director selector DS to the wiper 134. From this point the impulses traverse the operating conductor 36', armature 307 and its resting contact, conductor 241, series relay 201, Fig. 3, armature 231 and its resting contact, wiper 231 of the sequence switch SE and its first bank contact, conductor 262 to vertical magnet 420 of the office register OR. In response to the four impulses of current, the vertical magnet 420 raises the office register wipers 426-429 opposite the fourth level of bank contacts. Series relay 201, Fig. 3 energizes upon the receipt of the first impulse and maintains its armature 203 attracted throughout the entire series of impulses. At

armature 203 relay 201 closes a circuit for the associated slow acting relay 202 with the result that relay 202 energizes and prepares a circuit for magnet 208. It will be noted that armature 303, at its resting contact, opens the previously traced circuit for clutch magnet 405 of the timing device TD so that the timing device TD is returned to normal.

When the slow acting relay 201 falls back upon the termination of the series of impulses, it opens the circuit of relay 202 and closes, through the resting contact of armature 203 and through armature 204 and its working contact, a circuit for stepping magnet 208. Magnet 208 energizes and advances the wipers 212 and 213 of the sequence switch SE one step. After an interval, relay 202 falls back and opens the circuit of magnet 208.

When the calling subscriber dials the next character C, two impulses of current are transmitted to the director over the previously traced circuit as far as wiper 213 of the sequence switch SE, and, since wiper 213 is now on its second bank contact, the impulses are delivered over conductor 263 to the rotary magnet 419 of the office register OR. Accordingly, the wipers 426-429 are rotated two steps and are brought into engagement with the upper set of bank contacts shown in the drawing and labeled (42). By the operation of relays 201 and 202 the magnet 208 of the sequence switch SE receives another impulse of current and steps the wipers 212 and 213 into engagement with the third set of bank contacts. The grounded wiper 212 at this time places ground on conductor 354, thereby starting the transmission of impulses in a manner to be subsequently pointed out.

The series of impulses representing the first subscriber digit 6 is transmitted over the previously traced circuit to wiper 213 of the sequence switch SE and this series of impulses is delivered over conductor 264 to the stepping magnet 501 of the digit register DR-1, Fig. 6; the series of impulses representing the second subscriber digit 8 is transmitted over conductor 265 to the stepping magnet of the digit register DR-2; the series of impulses representing the third subscriber digit 2 is transmitted over conductor 266 to the stepping magnet of the digit register DR-3; the series of impulses representing the fourth subscriber digit 6 is transmitted over conductor 267 to the stepping magnet of the digit register DR-4; the series of impulses representing the station-designating character J and comprising five impulses is transmitted over conductor 268 to the stepping magnet of the digit register DR-5. In the above manner the digit registers DR-1-DR-5 are set in accordance with the thousands, hundreds, tens, units and stations-designating characters of the number, it being understood of course that the wiper 213 is advanced one step at the termination of each of the above

series of impulses. That being the case, wiper 213 lands on a dead contact at the end of the setting of the digit register DR-5 and the wipers 212 and 213 remain in this position until the director is released.

5 The description of the registration of the number having been completed, a description of the operation of the sending portion of the director will now be given.

10 Returning now to the point at which the wipers of the sequence switch SE advance from the second to the third position at the end of the rotary movement of the office register OR, the grounded wiper 212, upon 15 coming into engagement with its third bank contact, places ground on conductor 354. This operation renders the stop conductor control wiper 221 of the sequence switch SE' alive and extends a ground potential through 20 the first contact in the bank of wiper 220, conductor 251, armature 310 of relay 302 and its resting contact, and start conductor 321 to the pick-up springs controlled by the pick-up cam 330 of the sender. This does not produce 25 any particular results until the sender arrives in its pick-up position, at which time a circuit is closed through the springs controlled by the pick-up cam 330 for the upper winding of relay 306. Relay 306 energizes 30 over its pick-up winding and closes a locking circuit for itself at armature 319 to the stop conductor 342. Stop conductor 342 is at this time grounded over the following circuit: 35 from ground by way of the grounded conductor 354, Fig. 3, wiper 321 of the sequence switch SE' and its first bank contact, conductor 270, wiper 426 of the office register OR, the bank contact on which it is standing, the associated jumper which connects the 40 bank contact terminal of the I.D.F. with the terminal on the opposite side corresponding to four impulses and leading to the fourth impulse stop conductor (as indicated by the numeral 4 placed within the circle to the left 45 of the I.D.F.), the fourth impulse stop conductor, the springs controlled by the fourth impulse stop cam 334 of the sender, stop conductor 342, armature 319 and its working contact, and the lower winding of relay 306 to 50 battery.

As a further result of the energization of the combined pick-up and stop relay 306, a circuit is closed at armature 318 and over conductor 243 for stepping magnet 217 of 55 the sequence switch SE'. Magnet 217 energizes when this circuit is closed and operates the associated armature preparatory to advancing the wipers 218, 220, and 221 upon its subsequent deenergization.

60 As a still further result of the energization of relay 306, the shunt is removed from around the sending contacts controlled by the cam 341 of the sender. This is done at armature 317 of relay 306.

65 Following the operation of relay 306 and

the removal of the shunt from around the sending contacts, the cam 341 permits the sending contacts to open once after which they are again closed and the cam 331 disconnects the first impulse stop conductor from 70 conductor 342 so that, if the locking circuit of relay 306 is controlled over the first impulse stop conductor, relay 306 will fall back. The locking circuit is through the fourth impulse stop conductor at this time, however, 75 and relay 306 therefore remains energized until four interruptions have been produced in the outgoing control circuit at the sending contacts controlled by armature 341. At the end of the fourth interruption, the cam 334 80 opens the associated contacts with the result that relay 306 falls back and opens a further point in the locking circuit at armature 319; stops the transmission of impulses at armature 317 by shunting the sending contacts; 85 and at armature 318 opens the circuit of stepping magnet 217 of the sequence switch SE', with the result that magnet 217 falls back and advances the wipers 218, 220, and 221, one step. 90

The cams of the sender continue to advance, but nothing more is done toward the transmission of impulses until the pick-up position is reached the next time. It may be conveniently pointed out at this time that the spacings of the cams and cam cuttings are so arranged that in case the digit 0 is transmitted, which is the longest digit, enough time elapses following the termination of the last interruption of the outgoing control circuit to enable a selector switch to complete its trunk hunting operation before the pick-up position is reached the next time. 95

The effect of the transmission of the first code digit 4 will now be considered. Referring now to the selectors S, Fig. 1, line relay 51 falls back each time the outgoing control circuit is opened by the sender. Each time it falls back, line relay 51 closes at armature 56 a circuit through armature 58 and 105 its working contact, and series relay 53, for vertical magnet 68, which magnet is connected to battery through armature 21 and its resting contact of the switch-through relay 10 of the trunk circuit TC. By the operation 110 of vertical magnet 68, the wipers 72-74 are raised opposite the fourth level of bank contacts. Relay 53 is energized upon the first impulse of current and maintains its armature attracted throughout the series of impulses. At armature 59, relay 53 opens a point in the circuit of rotary magnet 69 and prepares a circuit for stepping relay 54, which is completed at off normal contacts 71 115 through the interrupter contacts 70, upon the closure of the off-normal contacts 71 when the shaft moves from its normal position. Relay 54 energizes over this circuit and prepares a circuit for rotary magnet 59 at armature 61 and it locks itself to ground at armature 120 125 130

ture 60 independent of armature 59 and its working contact.

At the end of the vertical movement of the selector S, relay 53 falls back and closes at armature 59 the circuit through armature 61 and its working contact for rotary magnet 69. Rotary magnet 69 energizes and advances the wiper 72-74 into engagement with the first set of bank contacts in the fourth level. 5 Near the end of its stroke, magnet 69 opens the interrupter contacts 70 with the result that relay 54 falls back and opens the circuit of the rotary magnet at armature 61. From this point the rotary operation of the selector S is similar to that of the director selector DS hereinbefore described. It will suffice to say that the rotary movement of the selector S continues until an idle trunk is reached, which trunk it will be assumed, is the one terminating in the bank contacts 75-77. 10 When this idle trunk is reached, switching relay 55 operates, but the stepping relay 54 does not due to the relatively high resistance of relay 55. At armature 63 relay 55 opens the test circuit and prepares the holding circuit, thereby grounding test wiper 73 to make the seized trunk busy immediately; opens at armature 64 the circuit of the slow acting release relay 52; and at armatures 62 and 65 15 disconnects conductors 5' and 7' from the windings of line relay 51 and extends them by way of wipers 72 and 74 and the bank contacts 75 and 77 to the line relay of the selector to which the seized trunk extends. 20

35 The line and release relays of the seized trunk now energize and the latter places ground on the associated release trunk conductor which closes a circuit through contacts 76, wiper 73, and armature 63 and its working contact to maintain the switching relay 55 energized after the slow acting release relay 52 has fallen back as it does shortly.

When the pick-up position of the sender is again reached, the pick-up winding of relay 306 is energized over the same circuit as before except that wiper 220 of the sequence switch SE' is now standing in its second position instead of the first. Upon operating relay 306 locks up over the following circuit. From ground by way of the grounded wiper 221 of the sequence switch SE' the second bank contact, conductor 271, wiper 427, the bank contacts on which it is standing, the 45 associated jumper, the third impulse stop conductor, the springs controlled by cam 333 of the sender, conductor 342, armature 319 and its working contact, and the lower winding of relay 306 to battery. The shunt remains disconnected at armature 317 from around the sending contacts until three interruptions have been produced in the outgoing control circuit, after which the cam 333 opens the above traced locking circuit 50 of relay 306 whereupon relay 306 falls back

and terminates the second code digit 3. The sequence switch SE' is advanced one step in the usual manner and the wipers are now in their third position.

Responsive to the transmission of the second code digit 3, the selector seized in response to the transmission of the first code digit 4 raises its wipers to the third level and selects an idle trunk line leading to an office selector. 70

When the sender arrives in the pick-up 75 position again, pick-up relay 306 again operates and at this time locks itself energized over the following circuit: from ground by way of the grounded wiper 221 of the sequence switch SE' and its third bank contact, conductor 272, wiper 428 of the office register OR, the bank contact on which wiper 428 is standing, the associated I.D.F. jumper, the eighth impulse stop conductor, the springs controlled by cam 338, and then to battery 80 through conductor 342, armature 319 and its working contact, and the lower winding of relay 306. Relay 306 remains energized until eight interruptions have been produced in the outgoing control circuit at the sending contacts after which the locking of relay 306 is opened at the springs controlled by cam 338. 85

Responsive to the transmission of the third code digit eight, the office selector seized in response to the transmission of the preceding 90 digit raises its wipers opposite the eighth level of bank contacts and selects a trunk line leading to an incoming selector in the Wichita office. 95

The wipers of the sequence switch SE' take 100 another step at this time and wiper 221 places ground on the fourth wiper 429 of the office register OR over conductor 273. The bank contact on which wiper 429 is standing is connected by means of a jumper on the I.D.F. 105 to the skip conductor 260. The result is that a circuit is closed over conductor 260 through the fourth contact in the bank of wiper 218 of the sequence switch SE' for stepping magnet 217 through the interrupter contacts 219. 110 Magnet 217 energizes over this circuit and opens the circuit at armature 219, whereupon the said magnet deenergizes and advances the wipers 218, 220, and 221 past the fourth code-digit position. Wiper 221 now places ground on the top wiper of the digit register DR-1 through conductor 278, preparatory to controlling the transmission of the first subscriber digit 6. Wiper 220, it will be noted, 115 breaks away from the grounded conductor 354 and makes contact with the grounded conductor 279 which is grounded at this time because the digit register DR-2, Fig. 6, is off normal. Otherwise the transmission of the first subscriber digit is delayed until the second subscriber digit register has gone off-normal, so as to insure that the sender does not attempt to send out a digit before it is registered. 120

When the sender again arrives in its pick- 125

up position, the upper winding of relay 306 is energized over the following circuit: from ground by way of the off-normal contacts 502 of the digit DR-2, Fig. 6, conductor 279, the fifth contact in the bank of wiper 220 and the said wiper, conductor 251, and then to battery over the previously traced circuit through the upper winding of relay 306. Relay 306 at this time locks itself energized over the following circuit: from ground by way of the grounded wiper 221 of the sequence switch SE', the fifth bank contact, conductor 274, upper wiper of the digit register DR-1, the sixth associated bank contact, the sixth impulse stop conductor, contacts controlled by cam 335 of the sender, and then to battery through armature 319 and its working contact and lower winding of relay 306.

Relay 306 accordingly remains energized until six interruptions have been produced in the outgoing control circuit at which time its circuit is opened by cam 335 thus terminating the first subscriber digit 6.

In a similar manner, the sender obeys the registration of the digit registers DR-2, DR-3, DR-4, and DR-5 and transmits the characters set up on these registers. It may be pointed out that, with the sequence switch SE' in position 6, corresponding to the register DR-2, the pick-up ground potential is placed on the pick-up wiper 220 of the sequence switch SE' through off-normal contacts 503 of the digit register DR-3 and through conductor 280; the pick-up ground potential for starting the transmission of the third subscriber digit is obtained through off-normal contacts 504 of the digit register DR-4 and through conductor 281 with the sequence switch SE' in its seventh position; the pick-up ground potential for the transmission of the fourth subscriber digit is obtained over the same path as the pick-up ground potential for the starting of the transmission of the third subscriber digit, as the fourth digit register DR-4 will have been in all cases sufficiently operated to insure that it cannot be overtaken by the sender as the sender must transmit the digit stored on the third digit register after the third digit register has gone off normal before it can start the transmission of the fourth subscriber digit; and the pick-up ground for starting the transmission of the digit representing the stations designation as registered on the digit register DR-5 is obtained through armature 203 of relay 201, Fig. 3, and its resting contact, conductor 257, off-normal contacts 505 of the digit register DR-5, conductor 282, and the ninth contact in the bank of wiper 220.

The sequence switch SE' advances another step at the end of the transmission of the stations-designating character, and wipers 218, 220, and 221 come into engagement with the tenth set of bank contacts. When this occurs a circuit is closed from the grounded

wiper 221, through the tenth associated bank contact, conductor 250, normally closed contacts controlled by armature 309, and the lower winding of switching relay 302 to battery. Switching relay 302 energizes and locks itself to the release trunk conductor 37' at armature 309, at the same time opening its initial circuit; opens at armature 310 a point in the pick-up circuit; introduces at armature 308 the resistance 301 in the outgoing-control circuit so as to cut down the current flow in this circuit preparatory to the operation of the switch through relay 10 of the trunk circuit TC, Fig. 1, and at armature 307 disconnects the incoming operating conductor 36' from the branch 241 and connects it to ground instead. This latter operation results in the energization of switch through relay 10 of the trunk circuit TC and in the short circuiting of the release relay 9. Release relay 9, however, remains operated for an interval. Upon energizing, relay 10 locks itself to release trunk conductor 6' at armature 40; joins the release trunk conductor 6 to the release trunk conductor 6' at armature 22; removes battery at armature 21 from vertical magnet 68 of the selector S for a purpose to be hereinafter explained; connects the incoming conductors 5 and 7 with the corresponding conductors 5' and 7' at armatures 20 and 23; disconnects line relay 8 at armatures 19 and 24; and at the normally closed contacts controlled by armatures 20 and 23 disconnects the conductors 5' and 7' from the outgoing control circuit of the director.

Line relay 8 falls back due to being cut off at armatures 19 and 24, and release relay 9 subsequently falls back due to its being short circuited initially upon the operation of the switching relay in the director and due to the local short circuit placed around its winding and the opening of its initial circuit upon the falling back of the line relay. Upon falling back, release relay 9 removes the local ground potential from release trunk conductor 6, leaving release trunk conductor 6 grounded from the release trunk conductor 6' through armature 22 and its working contact; opens a point in the previously established test circuit of the secondary switch SS at armature 18; and at armature 17 opens the circuit of the switching relay 11 and closes through armature 39 a circuit for the stepping magnet 30 of the secondary switch SS. Stepping magnet 30 now energizes preparatory to advancing the wipers 31-34. A moment later the switching relay 11 falls back and disconnects the wipers of the secondary switch SS, at the same time opening the circuit of the stepping magnet 30 at armature 39. Stepping magnet 30 falls back and advances the wipers of the secondary switch one step so that the next call will take a different director selector.

By the operation of the switches in the Wichita office the connection has now been

extended to the called line and the desired substation is now being signalled in the usual manner.

Responsive to the disconnection of the wipers of the secondary switch SS, release relay 104 of the director selector DS, Fig. 2, falls back and opens at armature 121 the circuit of switching relay 107 with the result that switching relay 107 falls back and disconnects the associated wipers. At armature 121 and its resting contact, relay 104 closes a circuit through off-normal contacts 109 for the release magnet 108 with the result that release magnet 108 energizes and restores the shaft and wipers of the director selector DS to their normal position in the usual manner. The circuit of release magnet 108 is opened at off-normal contacts 109.

In the director, the ground potential is removed from release trunk conductor 37' at the director selector DS when relay 107 falls back. There is a guarding potential maintained on conductor 37' at the director notwithstanding the removal of ground potential at the director selector. This alternate guarding potential is connected to conductor 37' through off-normal contacts 211 of the sequence switch SE, conductor 246, and relay 303. The resistance of relay 303 is fairly low, with the result that the director is maintained guarded for the time being. The net result of the removal of the ground potential from conductor 37' at the director selector is the removal of the shunt from around relay 303. Relay 303, therefore, energizes in series with release relay 304 and at armature 311 places ground through the low-wound relay 305 on the restoring conductor 320. This operation closes circuits for the release magnets of the digit registers DR-1-DR-5, for the release magnet 420 of the office register OR through off-normal contacts 425, and for the release magnet 209 of the sequence switch SE through armature 225 and its resting contact and off-normal contacts 210. As a result, the series guard relay 305 operates and disconnects release trunk conductor 37' from release relay 304 and connects it directly to ground again at armature 315. By this operation relay 304 is permitted to fall back whereupon it places a shunt around armature 311 and its working contact of relay 303 at armature 314; it closes at armature 312 a restoring circuit over conductor 245 for the sequence switch SE' which includes the multiple restoring bank, wiper 218, interrupter contacts 219 and stepping magnet 217; opens the circuit of the clutch magnet 405 of the timing device TD at armature 322; and at armature 313 it again removes the ground potential from wiper 212 of the sequence switch SE.

Responsive to the closure of the above mentioned restoring circuit, the various switches of the director are brought to their normal positions and when the last switch has been

released, the circuit of series relay 305 is opened, whereupon relay 305 falls back and disconnects release trunk conductor 37' from ground at armature 315 and reconnects it to relay 304 again, the upper terminal of relay 304 having been previously ungrounded at off-normal contacts 211 of the sequence switch SE.

Regarding the established connection, the two subscribers are able to converse with each other over the connection set up when the called man removes his receiver.

When the calling subscriber replaces his receiver, the ground potential is removed from the release trunk conductor of the established connection with the result that relay 55 of the selector S and relay 10 of the trunk circuit TC falls back. Relay 55 closes at armature 64 a circuit through armatures 56 and 58 and off-normal contacts 70 for release magnet 66 with the result that the wipers and shaft of the selector S are restored to their normal position in the usual manner.

Four-digit straight-line call

The description of the operation of the system in setting up a four-digit party-line connection having been given, the method of setting up the connection when a four-digit straight-line number is called will now be given. For this purpose it will be assumed that a calling subscriber desires connection with the subscriber whose number is listed in the director as WIChita 6926.

It will be assumed that the calling subscriber removes his receiver with the hereinbefore described results, and that when the first letter W is dialled the director selector DS, Fig. 1, seizes the director shown in Figs. 3-6. That being the case, when the second and third letters I and C are dialled, the wipers of the office register OR, Fig. 5, are brought into engagement with the second set of bank contacts in the fourth level, as before, and the transmission of the code digits is started upon the advance of the wiper 212 of the sequence switch SE into its third position at the end of the rotary movement of the office register OR.

The calling subscriber now dials the remaining portion of the number with the result that the digit registers DR-1-DR-4 are set in accordance with the designation 6926.

After transmitting the code digits in the hereinbefore described manner, the sender transmits the registered subscriber digits portion of the number, after which the wipers of the sequence switch SE' (which have, as hereinbefore described, advanced one step at the end of each digit) advance another step from their eighth position to their ninth position.

In the ninth position of the sequence switch SE' the sender is unable to start to transmit another digit owing to the fact that wiper 220

of the sequence switch SE' is in engagement with the ninth contact which is associated with the ungrounded conductor 282. This conductor is ungrounded it may be pointed out owing to the fact that the digit register

5 DR-5 is in its normal position.

Referring now to the timing device TD, the clutch magnet 405 of this timing device is energized upon the seizure of the director as hereinbefore pointed out. For convenience at this point, it may be pointed out that the circuit of the clutch magnet 405 is as follows: from ground by way of armature 203 of relay 201, Fig. 3, and its resting contact, 10 resting contact and armature 230 of relay 216, conductor 249, working contact and armature 322 of relay 304, conductor 252, jumper 418, and clutch magnet 405 to battery. Since the circuit of the clutch magnet includes normally-closed contacts of the relay 15 201, Fig. 3, the timing device TD is restored to its normal position each time a series of impulses is received.

It will be noted that the right hand spring 25 of the contact set 410 associated with the five second cam 402 is normally ungrounded, and that ground is placed on this spring only when the fourth digit register DR-4 goes off-normal. This means that the operation of 30 the five-second timing device is not effective until the setting of the digit register DR-4 has been completed, the timing device TD being restored to its normal position during the receipt of the series of impulses to operate the digit register DR-4.

Now, at the end of the setting of the digit register DR-4, relay 201 falls back and closes the above traced circuit for clutch magnet 405 of the timing device TD. The armature 404 is attracted and it swings the segment 403 and the cams 401 and 402 to the right so that the retaining springs 409 becomes effective, and so that, each time one of the wings 407 and 408 of the rotating shaft 406 passes up on the left-hand side of the shaft, the tooth segment 403 is advanced one step. The speed of the rotation of the shaft 406 is such that the enlarged portion of the five second cam 402 comes under the left-hand 50 spring of the contacts 410 at the end of five seconds. When this occurs, a circuit is closed from ground through the off-normal contacts 504 of the digit register DR-4, conductor 281, springs 410 associated with the cam 402 55 of the timing device TD, conductor 430, resting contact and armature 510 of relay 506, relay 507, and the associated resistance 511 to battery. Relay 507 energizes and at armature 512 closes a circuit from the grounded conductor 278 (this conductor is now grounded by wiper 221 in its ninth position), armature 512 and its working contact, conductor 250, normally closed contacts controlled by armature 309 of the switching relay 302, Fig. 60 4, and relay 302 to battery. Switching relay

302 now energizes with the result that the connection is switched through at the trunk circuit TC, and the director selector DS, Fig. 2, and the director shown in Figs. 3-6 are freed in the hereinbefore described manner.

70

Five-digit straight-line call

Assuming now that the director shown in the drawings is seized and operated in connection with a call to the subscriber whose number is WICHita 60266, the office register OR is set upon the second set of bank contacts in the fourth level and the digit registers DR-1-DR-5 are set in accordance with the subscriber digit of the number. Since the second subscriber digit is 0 in this case, the lower wiper of the digit register DR-1 comes into play to determine whether the number is a four digit number or a five digit number so as to prevent the simple switch-through operation at the end of the transmission of the fourth subscriber digit in case the number is a five digit number.

It is assumed that the trunking layout in each of the offices is such that the tenth level 90 of the hundreds selectors in the thousands groups 6-0 lead each to a special group of hundreds selector instead of to connectors as they do on the other levels. This is done so as to increase the capacity of the offices concerned beyond the ten thousand-line limit of a four digit system. It is assumed further that the 0 level of the hundred selectors in the thousands group 1-5 lead to connectors and not, therefore, to special hundreds selectors. Accordingly, the director has been arranged so that when the second digit dialled is 0 the director is transformed to a five-digit director in case the first digit is anything from six to 0, but is retained as a four-digit director in case the first digit is anything from one to five.

Now, since the second digit of the number at present under consideration is 0, and, since the first digit is six, the director must be prevented from switching through until the fifth digit register DR-5 has been operated.

The transmission of the digits necessary to complete the connection takes place in the manner hereinbefore described until the code 110 digits have all been transmitted and until the digit registered on the digit register DR-1 has been transmitted. At the end of the transmission of the first subscriber digit, the wipers of the sequence switch SE' advance 115 from their fifth position to their sixth position and the grounded wiper 221 places ground on conductor 275 leading to the wiper of the digit register DR-2. This results in a closure of a circuit through said wiper and through tenth contact in the associated bank, lower wiper and sixth contact of the digit register DR-1, normally closed contacts controlled by armature 509 of relay 506, and relay 506 to battery. Relay 506 ener- 120 125 130

gizes over this circuit and locks itself to the locking branch 248 of the release trunk conductor 37' at armature 509, at the same time opening its initial circuit. At armature 508, 5 relay 506 connects the extension of the wiper of the digit register DR-2 to the tenth impulse stop conductor so that the second registered subscriber digit 0 will be transmitted in the usual manner. It will be noted that relay 506 at armature 510 opens a point in the circuit of relay 507, which is the relay that brings about the switch-through of the connection at the end of the transmission of the fourth subscriber digit as hereinbefore pointed out. That being the case, the switch-through operation cannot be performed until the end of the transmission of the impulses representing the registration of the digit register DR-5. 10 15 20 25

20 The retransmission of the digits registered on the digit registers DR-3-DR-5 takes place in the hereinbefore described manner after which the grounded wiper 221 of the sequence switch SE' comes into engagement with the tenth associated bank contact with the result that the switching relay 302, Fig. 4, is operated in the hereinbefore described manner and with the result described.

I.D.F. arrangement

30 Regarding the novel arrangement of the terminals on the right hand side of the I.D.F. Fig. 5, it may be pointed out that sometimes a calling subscriber, in dialling the letters of 35 a number, mistakes the digit 0 for the letter O with the result ten impulses are sent instead of the intended six. At other times, the calling subscriber may mistake the digit 1 for the letter I with the result that only one impulse is transmitted instead of four. In order to correct this difficulty, the conductors joining the bank contacts of the office register to the right-hand side of the I.D.F. have been arranged so that the calling of the digit 40 45 50 55 60 65 0 has the same effect as the calling of the letter O and so that the calling of the digit 1 has the same effect as the calling of the letter I. For example it will be noted that in Fig. 5 the second set of bank contacts in the first level and the second set of bank contacts in the fourth level of the office register OR connect to a common set of terminals on the right-hand side of the I.D.F. This may be seen in Fig. 8, wherein the space corresponding to the second set of bank contacts in the first level is left vacant and the designation 12 is placed in the same square with the designation 42, similarly the placing of the designation 13 in the same square with the designation 43 is to indicate that the third set of bank contacts in the first level occupies the set of pins occupied by the third set of bank contacts in the fourth level. A study of Fig. 8, will reveal that only 64 sets of pin terminals are needed instead of the usual

100 sets. It will be understood of course that the regular 100 set could be provided in which case the combinations could be taken care of by jumpers at the I.D.F., but, since it is a permanent proposition, there is no need to combine the contact set by means of the more or less temporary jumpers, and as before stated, there is considerable saving in a reduction in the size of the terminal space necessary on the right hand side of the I.D.F. 70 75 80

Delayed dialling before first digit

It will be assumed now that a calling subscriber removes his receiver with the result that the secondary switch SS, Fig. 1, takes the director selector DS, Fig 2, into use, and that the calling subscriber fails to dial within the thirty seconds allotted for the first digit to be received. It will be remembered that release relay 104, Fig. 2, pulls up when the director selector is seized and at armature 116 closes a circuit for the clutch magnet 102 of the timing device TD'. This timing device is similar to the timing device TD, Fig. 5, except that the common actuating shaft of the timing device TD' (corresponding to the shaft 406 associated with the timing device TD) runs at a correspondingly slower rate. 85 90 95

At the end of thirty seconds, the cam 101 closes the contact 103 with the result that ground is placed on conductor 37. This results in the usual operation of the vertical magnet of the director selector DS. A further result is that, since the line relay 8 of the trunk circuit TC is energized at this time, the switching relay 10, being connected to conductor 39, is energized to switch the connection through in the usual manner. It will be noted that armature 21 of the trunk-circuit switch-through relay 10 removes battery from vertical magnet 68 of the selector S. This is done so as to prevent the calling subscriber from operating the selector S directly from his calling device in case he later starts to dial. 100 105 110

115 It will be noted that the battery supply of the release relay 52 of the selector S is taken through the relay 41. The relay 41 is common to a number of first selectors and, when any one of them is in the condition of having been seized and having not been operated, the common relay 41 is energized and the associated signal lamp 42 is lighted. The steady glow of the lamp 42 will indicate to an attendant when such a condition remains for a considerable length of time. The attendant may take such steps as he deems necessary to cope with the situation. 120 125

Delayed dialling after first digit

130 It will be assumed now that a calling subscriber removes his receiver and that the secondary switch SS, Fig. 1, responds by seizing the director selector DS, Fig. 1. It will be assumed further that the connection

is extended to the director shown in the drawings when the calling subscriber dials the first digit. It will be assumed still further, that the calling subscriber, either before or after dialling other digits, stops dialling before he has dialled the complete number. In this case the timing device TD is not released before the springs 411 are operated, as is the case when the calling subscriber continues to dial until the complete number has been registered. Upon the closure of the contacts 411, a circuit is completed from the grounded conductor 252 through the contacts 411, conductor 258, and the winding of relay 215 to battery. Relay 215 energizes and at armature 227 connects ground to conductor 249 independent of armature 203 and its resting contact of relay 201 so as to insure that the cycle of operations will be completed even though the calling subscriber should now begin to dial again. At armature 225, relay 215 disconnects the release conductor 269 from the branch leading to the release magnet 209 of the sequence switch SE and connects the main conductor 269 to ground, thereby releasing the operated registers. At armature 223, relay 215 connects ground to the bank of the restoring wiper 218 of the sequence switch SE' so as to restore that sequence switch to its normal position in case it has operated to transmit the stored portion, in case a part of the number has been dialled. At armature 224, relay 215 closes a local current for magnet 208 of the sequence switch SE, causing wipers 212 and 213 to take one step. At armature 226, relay 215 disconnects ground from wiper 212 of the sequence switch SE and closes an energizing circuit for relay 216. Relay 216 energizes and locks itself to the grounded release trunk conductor 248 at armature 220; prepares at armature 229 a start circuit independent of wiper 212; breaks the connection between conductors 257 and 249 at armature 230; opens the impulse circuit at armature 231; and at armatures 232-235 connects the first four conductors 270-273 leading from the banks of wiper 221 of the sequence switch SE' to the upper right-hand set of contacts at the I.D.F. preparatory to transmitting the digits necessary to trunk the call to the switchboard of the monitoring operator.

As a further result of the above energization of relay 215, it opens at armature 222 the outgoing control circuit, with the result that any partially-set-up connection is released.

After an interval which is sufficiently long to insure the release of any partially set up connection, the ten second cam 401 of the timing device TD, Fig. 5, permits the contacts 411 to open again, whereupon relay 215 falls back, leaving relay 216 locked up to the grounded release trunk conductor at armature 228. At armature 227, relay 215 removes ground from conductor 249 whereupon the

clutch magnet 405 of the timing device TD deenergizes and restores the timing device to normal. At armature 226, relay 215 connects ground from the grounded conductor 247 through the working contact and armature 229 of relay 216 to wiper 221, and through the first contact in the bank of wiper 220 to conductor 251. The result is that the sender transmits the digits determined by the connection of the upper right-hand contacts of the I.D.F. The first three contacts of this contact set are jumpered to the fourth, ninth, and second impulse stop conductors. The sender therefore, transmits the digits 4, 9, and 2 after which the grounding of the fourth contact by the wiper 221 of the sequence switch SE' results in a closure of a circuit through the jumper associated with the fourth contact in the set to the switching conductor 250 and through this conductor to battery through the switching relay 301, Fig. 4. The energization of this relay results in the switch-through operation being performed and in the director selector DS and in the director being released in the hereinbefore described manner.

It may be pointed out that the release of the sequence switch SE, Fig. 3, is prevented as hereinbefore pointed out so that the off-normal contacts 211 will supply ground to operate the relay 303, Fig. 4, to bring about the release of the apparatus in the director before the ground potential is removed from the release trunk conductor 37' in the manner hereinbefore described; and that the wipers of this switch are advanced one step by relay 215 to that, in case the sequence switch SE is not already off normal it will be moved off normal.

Wiping out preliminary impulses

Regarding the arrangement for wiping out the effect of the digit 1 on the director selector DS, Fig. 2, it may be pointed out that, when the series relay 105 falls back at the end of the digit 1, a circuit is closed at armature 124 through the contacts 111 and the off-normal contacts 109 for the release magnet 108. This results in the release of the director selector. In case the wipers of the director selector are raised opposite any other lever, the contacts 111 are separated and the above special release circuit is not closed. It is to be noted also that the circuit of stepping relay 108 remains open at contacts 112 when the digit 1 is received.

Two-digit office-destination system

In case the director shown in Fig. 3 is to be used in a somewhat smaller system, only two office designating digits are used and the director selector DS, Fig. 2, is omitted. In this case, the secondary switch SS, Fig. 1, extends the connection to a director upon the removal of the receiver. Therefore, Fig. 1, may be

placed above Fig. 4, with the conductors 35—38 in alignment with the corresponding conductors 35'—38' of Fig. 4.

When the director selector is omitted, certain minor changes in the circuit of the director are made. The jumper 414, Fig. 5, is cut and a jumper is connected between the terminals 413 and 415 so as to superimpose dial tone on the circuit of the vertical magnet to enable the calling subscriber to hear the dial tone when the connection is made to the director.

The jumper 418 in the circuit of the clutch magnet 405 of the timing device TD is cut and the timing device is therefore prevented from operating until the off-normal springs 424 of the office register OR shunt the gap left by the cutting of the jumper 418 when the office register OR goes off-normal.

The terminals 416 and 417 in the circuit of the clutch magnet 205 are connected by means of a jumper, with the result that a circuit is closed over off-normal spring 424 of the office register OR and its resting contact, the new jumper between terminals 416 and 417, and the conductor 256 for the clutch magnet 205 when the director is seized. This means that if the first digit is not received within thirty seconds the cam 206 of the timing device TD² operates the contact 201 to ground the switching conductor 250 to bring about the switch-through operation at the trunk circuit TC, Fig. 1.

Since the director is now reached upon the removal of the receiver, arrangements must be provided to wipe out the effect of the digit 1 of the office register OR. Accordingly, the terminals 421 and 422 are connected together by means of a jumper. Accordingly, if the office register OR now responds to the digit 1, a special circuit is closed upon the falling back of the series relay 201 and the associated slow acting relay 202. This release circuit is as follows: from ground by way of armature 203 and its resting contact, armature 204 and its resting contact, conductor 261, contacts 423 of the office register OR, the jumper now connecting terminals 421 and 422, off-normal contacts 425, and release magnet 420 to battery. A branch of this circuit extends by way of the common release conductor 269 and armature 225, to the release magnet 209 of the sequence switch SE through the off-normal contacts 210. Accordingly, the sequence switch SE and the office register OR are both restored to their normal position.

In order to enable the number of the zero operator to be transmitted upon the calling of the digit 0, an arrangement similar to that disclosed in my prior application Serial No. 573,175, filed July 6, 1922, may be employed, but this is not shown here in order to avoid unnecessary complication of the drawings.

What is claimed is:

1. In a telephone system, a register set, means for taking said register set for use, two timing devices, means for placing the register set under the control of the first of said devices responsive to said taking for use of the register set, means for registering a plurality of digits on said register set, and means responsive to the registration of the first digit for placing said register set under the control of the second of said devices. 75

2. In a telephone system, a register set, means for taking said register set for use, two timing devices, means for placing the register set under the control of the first of said devices responsive to said taking for use of the register set, means for registering a plurality of digits on said register set, and means responsive to the registration of the first digit for removing said register set from under the control of the first device and for placing it under the control of the second device. 85

3. In a telephone system, a register set, means for taking said register set for use, time-controlled means operated responsive to the taking for use of said register set for automatically freeing the same after a predetermined time interval has elapsed, means for registering a plurality of digits on said register set, and means responsive to the registration of the first digit for preventing the freeing means from operating because of the expiration of the said predetermined time limit, and for rendering said freeing means responsive to the expiration of a shorter time interval following the registration of any digit. 100

4. In a telephone system, a register set, means for taking said register set for use, a slow timer and a quick timer, means for starting the slow timer responsive to such taking for use of the register set, means for registering a plurality of digits on said register set, and means responsive to the registration of the first digit for restoring the slow timer and for starting the operation of the quick timer. 105

5. In a telephone system, a plurality of groups of directors, a director selector, means for taking said director selector for use, a slow timer associated with said director selector, a quick timer associated with each of said directors, means responsive to the taking for use of said director selector for starting said slow timer, means for operating said director selector to select a director in a desired group, means responsive to this operation for restoring the slow timer, means for registering a plurality of digits in said director, and means controlled by said quick timer for freeing the director at the end of a short interval of time in case such time interval expires following the seizure of the director and before the first digit is regis- 115 120 125 130

tered, and also in case such time interval elapses between the dialling of successive digits.

6. In a telephone system, a director selector, a plurality of groups of directors accessible to said director selector, means for taking said director selector for use, means for operating said director selector in accordance with a digit in a telephone number to seize a director in the corresponding group, registering means in the seized director for registering a plurality of digits in said telephone number, means controlled through said director selector for freeing said director selector at the end of a given time interval following its being taken for use in case the said director selector has not been operated at the end of such time interval, and means controlled through the seized director for freeing the director and the director selector at the end of a shorter time interval in case such time interval elapses between the seizure of the director and the registration of the first digit or between the registration of successive digits.

7. In a telephone system, a director including a plurality of digit registers operable in accordance with the digits in a telephone number and an impulse sender operated under the control of said registers to transmit series of impulses, means responsive to a delay between the dialling of successive ones of said digits for operating said sending mechanism to transmit a predetermined combination of digit impulses, another digit register in said director, means for operating said other digit register after the others have been operated, and means responsive to a lesser delay in the operation of the last named digit register for freeing the director without transmitting said predetermined combination of digit impulses.

8. In a telephone system, a director comprising a plurality of digit registers and a sender, means for operating a variable number of said digit registers and for operating said sender to transmit series of impulses in accordance with the operated ones of said registers, means responsive to a delay in the operation of successive registers for transmitting a special number, and means responsive to a delay in the operation of the last of said digit registers for freeing said director without transmitting said special number.

9. In a telephone system, a director including registering means for registering a plurality of digits and a sender for transmitting impulses under the control of the registers, means for taking said director into use and for automatically freeing said director responsive to the operation of the sender under the control of the last of said registers, and means controlled in accordance with the setting of one of said registers for preventing the said freeing of said director.

10. In a telephone system, a director including registering means for registering a plurality of digits and a sender for transmitting impulses under the control of the registers, means for taking said director into use and for automatically freeing said director responsive to the operation of the sender under the control of the last of said registers, means for registering and for controlling said sender to retransmit another digit, and means for freeing said director after the retransmission of the last-named digit.

11. In combination, a register switch having 100 sets of bank contacts, a distributing frame having 64 sets of terminals, and permanent, systematically-arranged connections between the bank contact sets and the distributing-frame terminal sets whereby all the bank contact sets are represented by terminal sets of the distributing frame, certain terminal sets representing only one bank contact set, and other terminal sets representing a plurality of bank contact sets.

12. In combination, a register switch having a plurality of sets of bank contacts, a distributing frame having a lesser plurality of sets of terminals, and permanent systematically-arranged, connections between the bank contact sets and the distributing-frame terminal sets whereby all the bank contact sets are represented by terminal sets of the distributing frame, certain terminal sets representing only one bank contact set, and other terminal sets representing a plurality of bank contact sets.

13. In a combination, a two-digit register switch having a plurality of contacts designated by separate two-digit numbers, a distributing frame having a lesser plurality of terminals, and permanent connections between said terminals and said contacts such that certain terminals are connected to a plurality of contacts the numbers of which have one digit in common, the other digit being different for each of such numbers.

14. In a multi-office telephone system employing register senders, connections in the register sender such that the dialling of two or more separate office designations results in the call being trunked to the same office in each case.

15. In a telephone system employing register senders and using calling devices on which the digit 1 and the letter I correspond to different digits, connections in the register senders whereby the dialling of one of said designations results in the same operation of the part of the sender as the dialling of the other designation.

16. In a telephone system in which register senders are employed and in which the digit 0 and the letter O correspond to different digits, connections in the register senders such that the dialling of either of said designations produce the same result as regards

the sender as the dialling of the other designation.

17. In a telephone system employing register senders and employing calling devices having the digit 1, the letter I, the digit 0, and the letter O, all in different positions in the calling device, circuit arrangements in the register senders, such that the dialling of the digit 1 has the same effect upon the sender as the dialling of the letter I, and such that the dialling of the letter O has the same effect upon the sender as the dialling of the digit 0.

18. In a combination, a register sender including means for registering and retransmitting a plurality of digits, means for seizing said register sender, means responsive to the registration of a certain one of said digits for freeing said register sender, and means for preventing the last named means from freeing the register sender until all the registered digits have been retransmitted.

19. In a combination, a register sender including means for registering and retransmitting a plurality of digits, means for seizing said register sender, means responsive to the registration of a certain one of said digits for freeing said register sender at the end of a predetermined time interval following the registration of such digit, and means for preventing the director from being freed until all registered digits have been retransmitted in case any remain unretransmitted at the end of such time interval.

20. In combination, a plurality of contacts, means for operating said contacts one at a time in a definite order and in cycles, a normally ineffective impulse sender, a relay for rendering said sender effective, an energizing circuit for said relay closed momentarily upon the operation of one of said contacts, and a locking circuit for said relay including any one of the remaining contacts.

21. In a telephone system, a director comprising a plurality of digit registers and a sender, means for taking said director for use and for automatically freeing said director responsive to the elapse of a predetermined time interval following the registration of a digit on the next to the last of said digit registers and subject to the retransmission of such digit by said sender, and means responsive to one of the preceding registers having been set in a particular position for preventing the said freeing of the director.

22. In a telephone system, a director comprising a plurality of digit registers and a sender, means for taking said director for use and for automatically freeing said director responsive to the elapse of a predetermined time interval following the registration of a digit on the next to the last of said digit registers and subject to the retransmission of such digit by said sender, and means responsive to one of the preceding registers having been set in a certain position for pre-

venting the said freeing of said director in case the register preceding the said preceding one is set in any one of a plurality of positions.

23. In a telephone system, a director comprising a plurality of digit registers and a sender, means for taking said director for use and for automatically freeing said director responsive to the elapse of a predetermined time interval following the registration of a digit on the next to the last of said digit registers and subject to the retransmission of such digit by said sender, means responsive to one of the preceding registers having been set in a particular position for preventing the said freeing of the director, and further means for causing the director to be freed at the end of a longer time interval following said registration in case the last digit register is not operated.

24. In combination, a plurality of contacts, means for operating them one at a time in a definite order and in cycles, an impulse sender, relay mechanism, and circuit connections such that said relay mechanism is caused to render said sender effective responsive to the operation of one of said contacts and is caused to render said sender ineffective responsive to the operation of any one of the other contacts.

25. In a telephone system, a plurality of directors, each including registering and retransmitting apparatus, separate timing devices individual to the directors, respectively, freeing means in each director controlled jointly by the associated registering, retransmitting, and timing apparatus, and a mechanical driving shaft common to all said timing devices.

26. In a telephone system wherein impulses in sets corresponding to the digits of telephone numbers are transmitted over calling lines to the telephone exchange to indicate the called lines and wherein apparatus is provided for associating registering apparatus with a calling line when a call is made and for disassociating such apparatus from the line after the registration has been effected, means including timing apparatus for operating the said disassociating means at the end of a predetermined time interval following the association thereof in case the first digit of the number has not been received during such interval, and for operating the disassociating means at the end of a shorter interval following the receipt of the first digit in case the second digit has not been received during such interval.

27. In a telephone system wherein connections are set up over trunk lines through automatic switching apparatus controlled by impulses transmitted from register senders set over such trunk line from calling lines, each of said trunk lines having a condenser shunted across the talking conductors thereof

to aid in smoothing out the switch-operating impulses transmitted over the respective trunk lines by the register senders, and means for disconnecting each of said condensers from across the talking conductors after all of the switch-operating impulses incidental to the connection have been transmitted.

28. In a telephone system employing register senders, a trunk line, branch connections extending from said trunk line, means for associating a register sender with said trunk line over said branch connections, means for transmitting switch-operating impulses to said trunk line over a pair of conductors included in said branch connections, an impulse-smoothing condenser connected across said pair of conductors, and means for disconnecting said branch connections from said trunk line after all the impulses have been transmitted.

29. In a telephone system, register senders divided into groups, a register sender selector having access to said groups, means for operating a register sender selector over a calling line to extend a connection to a register sender in a desired group, and means for transmitting busy tone current back to the calling line in case all the register senders in the desired group are busy.

30. In a telephone system wherein register senders are set in accordance with digits in desired telephone numbers over branch connections from trunk lines, a conductor included in each branch connection for conducting the impulses to a register sender, circuit connections for transmitting tone current over said conductor and to a calling line when connection is made with a trunk line, means for testing a plurality of register senders, and means effective in case all of them are busy for applying busy tone current over said conductor to the calling line.

In witness whereof, I hereunto subscribe my name this 6th day of January, A. D. 1926.

MARTIN L. NELSON.
